JOSEPH L. JAFFE AND ROBERT J. MONROE, OF CLEVELAND, OHIO, ASSIGNEES TO THE
PERFECLITE COMPANY, OF CLEVELAND, OHIO, A CORPORATION OF OHIO

LIGHTING FIXTURE

Application filed January 12, 1927. Serial No. 160,736.

This invention relates more particularly to lighting fixtures of general adaptability, and it is among the objects of the invention to provide a construction capable of holding standard lamp equipment, and in a manner positive and simple. Other objects and advantages will appear as the description proceeds.

To the accomplishment of the foregoing and related ends, the invention, then, consists of the features hereinafter described, and particularly pointed out in the claims, the following description and the annexed drawing setting forth in detail certain construction embodying the invention, such construction however illustrating but several of the various ways in which the principle of the invention may be used.

In said annexed drawing:—

Fig. 1 is a central longitudinal sectional view showing an embodiment of the invention; Fig. 2 is a rear elevational view; and Fig. 3 is a similar view with another form of socket.

The reference character 1 in the drawing designates a wall plate or canopy made up of glass, porcelain, or other suitable material, and having attaching means, for instance, a plate or strip 2 seating at each end in recesses 3 and held by screws 4. The member 1 is provided with a central bore, the inner part 5 of which extends to a ledge or shoulder 6, preferably by a slight convergence or taper; and the reduced outer portion 7 of which is cylindrical. Externally it is screw-threaded, and engaging on such thread is a clamp-ring 8 which on being set up from the inside of a shade 9 of any desired form holds its securely against the canopy. The bore 5, 7, is adapted to receive a lamp socket S, a lateral recess 10 allowing the seating of a lug projection 11 thereof, and this together with the wedging taper of the bore, where availed of, holds the socket against turning, and in this manner standard keyless, key or pull chain sockets may be used. Where a pull-chain socket is used, the chain-guide 12 thereof seats in the recess 10, and the chain extends out through the opening 13. Ordinarily an additional securing means for the socket is desirable, and for this, a clip or the like 14 may be fastened

by a screw or bolt to the canopy inside so as to lap over back of the socket as in place in the bore.

It will thus be seen that the construction as a whole provides a shade holder adaptable to shades of wide variety of contour and size, and using standard sockets, without necessity of any additional adapter element or modification of the socket. Moreover by reason of the manner of fastening the socket, that is, entirely within the canopy, there is no danger of the socket being displaced when a lamp is changed or when the shade is taken off or replaced, the holding means in each instance being entirely independent.

Other modes of applying the principle of the invention may be employed, change being made as regards the details disclosed, provided the means stated in any of the following claims or the equivalent of such be employed.

We therefore particularly point out and distinctly claim as our invention:—

1. In a lighting fixture, the combination of a canopy having a bore to hold a lamp socket, and clip means attached to the canopy for restraining the socket against rearward displacement.

2. In a lighting fixture, the combination of a canopy having a bore to hold a lamp socket, and a swingable clip back of the socket and fastened to the canopy for securing the socket in the bore.

3. In a lighting fixture, the combination of a canopy having an un-turnable external thread at its outer end, and a clamping ring engaging thereon for securing a shade, said canopy having a bore to receive a lamp socket, and means within the canopy for holding the socket against turning.

4. In a lighting fixture, the combination of a canopy having an un-turnable external thread and having a bore with a lateral recess at the rear portion to hold a lamp socket and socket projection respectively, a clamping ring engageable on said external thread for securing a shade, and means behind the socket for securing the socket in place.

5. In a lighting fixture, the combination of a canopy externally threaded at its outer end,

a clamping ring engaging thereon for securing a shade, said canopy having a tapered bore to receive a lamp socket, and means back of the socket and secured to the canopy for holding the socket in the bore.

- 5 6. In a lighting fixture, the combination with a canopy having a body portion and being reduced and externally threaded at its outer end with a shoulder, a back plate for
10 said canopy, and fastening screws for said back plate extending through said shoulder, of a shade having a neck portion fitting over said end and an internally threaded clamping ring engaged with said end interiorly of said neck and holding said neck in close abutment with said shoulder and in concealing relation to said screws.

Signed by us this 23 day of December, 1926.

JOSEPH L. JAFFE.

ROBERT J. MONROE.
